(57) **CLAIM**

The ornamental design for a sheet stowage container, as shown and described.

DESCRIPTION

FIG. 1 is a front, right-side, top perspective view of the sheet stowage container;
FIG. 2 is a front elevational view thereof;
FIG. 3 is a rear elevational view thereof;
FIG. 4 is a top plan view thereof;
FIG. 5 is a bottom plan view thereof;
FIG. 6 is a left-side elevational view thereof;
FIG. 7 is a right-side elevational view thereof;
FIG. 8 is a front, right-side, top perspective view thereof in a first open configuration;
FIG. 9 is a front, right-side, top perspective view thereof in a second open configuration; and,
FIG. 10 is a top plan view thereof in a disassembled configuration.

The short dash-short dash-long dash lines shown in the figures depict score lines that assist in hinged bending. The short dash-short dash-long dash lines form part of the claimed design. The broken lines shown in the figures depict a perforated edge to assist in tearing. The broken lines form part of the claimed design.

1 Claim, 8 Drawing Sheets
